UNITED STATES PATENT OFFICE

LORY J. MILDREN, OF PONCA CITY, OKLAHOMA, ASSIGNOR TO HINDERLITER TOOL COMPANY, OF TULSA, OKLAHOMA, A CORPORATION OF OKLAHOMA

CASING AND TUBING SUPPORT

Application filed January 28, 1930. Serial No. 424,099.

This invention relates to casing heads and tubing supports and the primary object of the invention is to fasten the tubing support to the casing head in an efficient manner.

5 The novelty of the invention will be understood by reference to the following description in connection with the accompanying drawings in which:

Fig. 1 is a view partly in section and partly 10 in elevation of a casing head and tubing support constructed in accordance with my invention and

Fig. 2 is a sectional view on the line 2—2 of Figure 1.

15 The casing head is shown as consisting of two members 1 and 2. The ring member 1 is provided with a skirt 3 to which a cylindrical member 4 is provided with outlet ports 5 and 6 and it has a skirt 7 to which the casing 8 may be screwed, there being a packing 9 in the shoulder 10 of the cylindrical member 7 upon which the end of the ring 1 may rest. The ring 1 is provided with an internal shoulder 11 to receive packing 12 forced against 20 the shoulder by the conical skirt 13 of the spider 14 which carries the slips 15 to hold the tubing 16 in place. The ring 1 is provided with opposite lugs 17 and 18 to align with similar lugs 19 and 20. The lugs 19 25 and 20 carry bails 21 and 22 by means of which the spider may be lifted and lowered. The spider is removably fastened to the ring 1 by the U-bolts 23 and 24, carrying the bars 25 and 26 and nuts 27 and 28. Therefore, 30 the spider and casing head can be securely fastened in a manner to permit the spider to be easily detached from the head should occasion demand.

35 It will also be apparent that the head can be made up of a plurality of members and efficiently packed where the members are joined as well as provide packing around the tubing. Whenever it is desirable to fasten all the parts together, the U-bolts can readily be put in place as shown in Figure 1 or as 40 readily removed when detaching the spider.

45 What I claim and desire to secure by Letters Patent is:—

50 A casing head and tubing support comprising two members, one of which is pro-

vided with a skirt, the other member being screwed to the skirt, the first member having outstanding lugs, the second member having outlet ports to receive pipe and a skirt to which the tubing can be secured, a spider 55 receivable in the first member, packing rings upon which the spider rests, lugs on the spider, loose connections connecting the first member and the spider, and bails connected to the spider.

60 In testimony whereof I affix my signature.

LORY J. MILDREN.
